UNITED STATES PATENT OFFICE.

RUDOLPH JOHNSON, OF MINNEAPOLIS, MINNESOTA.

LATH ANCHORING AND SUPPORTING DEVICE.

Application filed September 30, 1925. Serial No. 59,528.

This invention relates to anchoring or retaining devices for the ends of laths or other analogous members employed to form a wall. While it is capable of wide general use, in 5 building, it is especially adapted to anchor the ends of a plurality of laths forming a wall having a diagonally extending side.

It is often necessary in erecting a stairway or the wall extending up to the roof 10 of a building, to provide some means for securing and anchoring the ends of the laths employed which terminate between the pieces of studding.

Hitherto, two by fours or other stringer 15 members have been sawed at an angle at their ends and diagonally disposed between the studding to furnish a support to which the diagonally disposed ends of a plurality of laths could be secured. The preparation 20 or cutting of these several short pieces adapted to extend diagonally between the studding has always necessitated a considerable amount of work on the part of the carpenter erecting the wall about a staircase or 25 other diagonally extending building structure.

It is the main object of this invention to provide an extremely simple but highly efficient anchoring strip which may be supported from the furring board of a stairway or any suitable supporting surface adjacent the wall formed by the laths, having 30 means for engaging the adjacent ends of a plurality of laths to support and anchor 35 the same for plastering.

It is a further object of the invention to provide a lath anchoring and supporting strip adapted to be attached to any vertically or diagonally extending support- 40 ing surface and having a longitudinal seat of substantially U-shaped cross section adapted to anchor the ends of a plurality of laths forming a wall.

A still further object is to provide such a 45 device constructed from a single elongated sheet of preferably resilient sheet metal bent or pressed to form an attaching base and a seat of U-shaped cross section disposed at an angle thereto and having a re-enforced 50 side and bottom.

An additional object of the invention is to provide said anchoring strip with means whereby the ends of the laths or analogous members may be nailed or otherwise secured 55 thereto.

These and other objects of the invention will be apparent from the following description made in connection with the accompanying drawings, wherein like characters refer to similar parts throughout the several 60 views, and in which—

Fig. 1 is a vertical section of a stairway showing the adjacent wall in elevation with the preferred form of the invention employed to retain the diagonally arranged 65 ends of the plurality of laths forming the wall;

Fig. 2 is a vertical section taken on the line 2—2 of Fig. 1 with some parts broken away;

Fig. 3 is a fragmentary side elevation 70 of the preferred form of the invention;

Fig. 4 is a cross section taken on the line 4—4 of Fig. 3; and

Fig. 5 is a horizontal section showing the preferred form of the device employed on 75 a vertically disposed building member extending between a beam and the floor of a room.

In Figs. 1 and 2 the usual vertically parallel spaced studding, is indicated by the 80 numeral 6 having secured thereto and extending diagonally there-across, the furring board 7 for the stairway. The usual stringer 8, cut out to form the steps, is secured flush against the furring board 7 and the 85 step boards 9 and 10, respectively, are supported and secured to stringer 8 and the stringer (not shown) on the opposite side of the stairway. A plurality of laths 11 are secured transversely of the studding 6 90 and spaced slightly apart in the usual manner for the plaster and having their ends adjacent the furring board by necessity diagonally arranged.

The anchoring and supporting device, des- 95 ignated as an entirety by the letter A, for the ends of the laths, is constructed from an elongated strip of preferably somewhat resilient sheet metal. This strip is bent on a line parallel with its sides to form a relatively wide base portion 12 and an elongated seat of substantially U-shaped cross section extending preferably at right angles thereto, having a re-enforced inner side 13 formed of two thicknesses of the strip, an 100 outer side 14 of one thickness of the material extending substantially to side 13, and a re-enforced bottom portion 15 of two thicknesses of the material. To form this structure, an elongated strip of metal is first bent 110

upwardly at an angle of approximately 90°, then bent down inwardly flush against the perpendicular side so formed, then bent outwardly to form the bottom portion of the seat flush against the base portion 12 and again bent upwardly at an angle of approximately 90° to form the outer side portion 14 of the seat.

In the outer side 14 of the seat a plurality of longitudinally spaced relatively large apertures 14^a are provided, adapted to retain the plaster about the sides of the device and ends of the laths. Side 14 is also provided with a plurality of relatively small longitudinally spaced apertures 14^b through which nails may be passed to positively secure the anchoring device to the ends of the laths if desired. A relatively narrow flange 12^a may be down-turned from the base portion 12 to properly align the device with the edge of a board or supporting surface on which it is applied.

In Fig. 5 the device is shown applied to a vertically disposed board or member 16 extending between a beam 17 and the floor of a room. The laths 11 in the wall here formed terminate in a vertical line. Plaster 18 is illustrated adhering to the laths 11 and outer sides 14 of the anchoring device A.

The functions and use of the device will probably be obvious from the foregoing description but may be briefly summarized as follows:

In Figs. 1 and 2 the base portion 12 of the anchoring device is secured by nails or other suitable means to an edge of the furring board 7 with the elongated seat disposed in alignment with the laths 11. The ends of the laths 11 adjacent the furring board are inserted in the seat of the anchoring device as they are nailed to the studding and are embraced by the sides 13 and 14, and supported and retained within said seat. If desired, the laths may be nailed to the anchoring devices through the apertures 14^b. It will be seen that the several laths which terminate between the several pieces of studding, falling short thereof, will be anchored and supported by the diagonally disposed strip A. Likewise, it will be seen in Fig. 5 that the strip may be employed in vertical position where required. Apertures 14^a in the outer sides 14 provide sufficient irregularities for the retention of the plaster.

From the above description, it will be seen that an extremely simple but highly efficient device of the class described has been invented and can be manufactured at little cost, and will eliminate a great deal of labor and expense in constructing walls within a building, obviating the necessity of diagonal stringers between the studding. Extensive actual usage of the device has shown

the same to be highly successful for all of the purposes intended.

It will, of course, be understood that various changes may be made in the form, details, proportions and arrangement of parts without departing from the scope of the invention.

What is claimed is:

1. A device of the class described, comprising an elongated strip having a relatively wide base portion adapted to be secured to a supporting surface, an elongated seat of substantially U-shaped cross section extending substantially at right angles to said base portion and adapted to receive and anchor the ends of a plurality of laths or analogous members and a flange at one side of said base portion adapted to abut the edge of a supporting surface. 75

2. A device for anchoring and supporting the ends of a plurality of laths or analogous members, comprising an elongated member having a base portion and a downturned flange at one side thereof, said base portion having means thereon for attachment to a supporting surface with said flange abutting one edge of the supporting surface, said member projecting upwardly at substantially right angles to said base portion and being reversely bent to extend downwardly from said upwardly projecting portion to said base portion, then being bent at right angles to extend along said base portion for a short distance, to be again upwardly bent at substantially right angles to said base 100 portion. 85

3. The combination with a plurality of parallel spaced members, a diagonally disposed member secured there-across, and a plurality of laths or analogous members secured across said spaced members to form a wall terminating adjacent the sides of said diagonal member, of a device of the class described comprising an elongated member having a base portion secured to an edge of said diagonally disposed member and an elongated seat of substantially U-shaped cross section adapted to embrace and anchor the adjacent ends of said laths or other members. 105

4. The combination with the studding of a building, an elongated strip secured diagonally across said studding, and a plurality of laths or analogous members secured to said studding and terminating adjacent said strip, of an elongated member having a base portion secured to an edge of said strip, a downturned flange on said member abutting a side of said strip and an elongated relatively narrow seat formed in said member at substantially right angles to said base portion, within which the terminals of said laths or analogous members are anchored. 110

In testimony whereof I affix my signature.

RUDOLPH JOHNSON.
